UNITED STATES PATENT OFFICE.

ALFRED CARL OHEIM, ALFRED SYHRE, AND OTTO HENTSCHEL, OF LEIPZIG, GERMANY, ASSIGNORS TO THE FIRM EMIL GERASCH G. M. B. H., OF LEIPZIG, GERMANY.

METHOD AND APPARATUS FOR THE PRODUCTION OF PRINTS.

Application filed August 16, 1923. Serial No. 657,778.

To all whom it may concern:

Be it known that we, ALFRED CARL OHEIM, ALFRED SYHRE, and Otto HENTSCHEL, citizens of the German State, residing at Leipzig, in the State of Saxony, Germany, have invented certain new and useful Improvements in and Relating to an Improved Method and Apparatus for the Production of Prints, of which the following is a specification.

It has already been proposed, when making proof impressions, so-called pulls, to use the ordinary lithographic hand-press for obtaining offsets. This, however, entails a structural modification of the press to the extent that a hinged frame, in which the elastic cloth is stretched, must be provided and that the scraper of the press must be replaced by a special roller. It has also been proposed to use for the same purpose a divided frame, in the lower part of which the form is clamped, while the rubber cloth is clamped, to two sides in a hinged frame, a third frame being provided between the other two frames, in which the paper to be printed is stretched. In this case as well the pressure of a roller is employed, when the lithographic hand-press is used. In both the above mentioned cases the transfer of the impression to the rubber cloth is effected by the latter being laid on the form, that is by direct contact of the cloth with the printing surface, which, apart from the fact that the cloth is stretched only to two sides, which always causes the two other edges of the cloth to curve inwards more or less, is one of the principal causes of bad work and so-called smudging and doubling.

The subject of the present invention is a method and an apparatus for carrying out the method of producing prints of all kinds, whereby in an ordinary lithographic hand-press without any structural modifications of the same, that is, by using the scraper of the press and a double frame, which is adapted to rest on the carriage of the hand press and to contain the form and the stretched rubber cloth, to produce prints from all forms in low and high relief and of letter press forms, both directly and indirectly, and hence also for pulls suitable for offsets. It has hitherto not been possible to carry out all such work in cylinder or platen presses.

The invention consists substantially in a particularly advantageous way of utilizing

the vertically acting pressure of the scraper of the lithographic hand-press, by the rubber cloth, which is stretched tightly in the upper hinged part of the double frame, does not touch the form, when the frame is closed and is provided in the usual manner with a protective covering, said cloth being brought against the printing surface by means of the vertically acting scraper and the impression being thus produced.

The peculiarity of this method consists in this, that, owing to the small distance of the rubber cloth from the form and to its being uniformly and tightly stretched, which prevents it from being pulled in at the sides, the pressure of the scraper always causes the contact between the rubber cloth and the form to take place in a progressive, straight line, as the elastic cloth always keeps its distance from the form immediately in front and immediately behind the edge of the scraper.

Owing to the rubber cloth being stretched extremely tightly and uniformly in all directions, the pressure of the scraper will not exceed the tension of the cloth by more than is necessary for the contact of the rubber cloth and the surface of the form for obtaining a clean print, and by this means any "working" of the rubber cloth on the form is prevented and a perfectly sharp print is always assured.

This way of stretching the rubber cloth, which is effected by the said cloth being firmly fixed at two opposite edges of the hinged frame and held at the two other sides of the frame by easily displaceable clamping devices, which, on the rubber cloth being stretched and the front movable limb of the frame being adjusted for this purpose, are adapted to give until the required tension in the rubber cloth is obtained, in which position it is then secured by fixing the clamping devices, provides the possibility of making indirect prints of all kinds, even from flat forms and on the roughest paper or the like, as the requisite pressure is obtained from the powerful action of the pressure of the scraper and the counter-action of the tension of the cloth. A further advantage of the present method and of the apparatus for carrying out the same consists in this, that it may be used for copying directly on to zinc plates, such as are used for making offsets. It should be specially mentioned

that the foil used as a negative for this purpose can be printed on indirectly and directly at the same time and that by this accurately superposed printing on both sides 5 the impressions are caused to register particularly well.

The foil used in place of a glass negative, for instance a thin gelatine sheet, tracing or transparent paper and the like, may be 10 printed on directly and indirectly, in other words on both sides at the same time in one operation, in the following manner:—

After the form, which is held in the double frame, has been inked, an impression of it is 15 made on the rubber cloth. The form is thereupon inked again and an impression made on the sheet of gelatine placed between the form and the rubber cloth. The print thus obtained, on which the front and back 20 impressions are in perfectly sharp register, ensures in the first place a sufficiently good register for copying purposes and consequently an equally sharp copy, irrespective of whether it is illuminated for obtaining a 25 direct or an indirect print. In every case a colour covering layer will be caused to lie on the copying layer.

According to previous processes for the production of negatives it was impossible to 30 obtain a sharp print, as the printed side could not be placed on the copying sheet, and thus lack of sharpness resulted, varying according to the thickness of the sheet. According to the invention this is prevented in 35 that the negative transferred on a rubber cloth is transferred on a thin sheet of foil in one operation with the production of another negative, this foil being laid between the printing stone (lithograph) and the rubber cloth and the latter pressed against the foil while, if required, another sheet lying 40 under the foil or also the same sheet may be printed on both sides. There is thus obtained a foil by means of which negative as 45 well as positive copies may be made, as the printed surface lies directly on the copy to be made.

Thus, for instance, it is possible to obtain 50 negative foils from engravings, by inking the surface of the engraved form with the roller and conversely to obtain negative foils from etchings, by inking with the tympan.

As the method of offset printing has such 55 a number of applications, the use of the foils may also be very varied.

A constructional example of the apparatus for carrying out the method is shown in the drawing:—

Fig. 1 shows the apparatus open and without 60 the rubber cloth in perspective.

Fig. 2 is a side elevation with the rubber cloth in position, looking in the direction opposite to the arrow B in Fig. 1.

Fig. 3 is a plan view looking in the direction C of Fig. 1,

Fig. 4 is a cross-section through the closed form, during the taking of an impression,

Fig. 5 is a view from above of a clamping bar for the rubber cloth,

Fig. 6 is a cross-section through one of the 70 side members of the frame on line A—A of Fig. 1, with the rubber cloth in position.

Fig. 7 is a fragmentary perspective view of one of the side members of the frame showing the rubber cloth in section. 75

The form 1 is fixed into a frame *a*, which is laid on the carriage of the lithographic hand-press, the frame being provided with clamping screws *d* for this purpose. Adjusting screws *b* are fitted in the frame *a* and project below the bottom surface of the latter. These screws are adapted to rest upon a table or other support on which the form 1 is disposed and thus by uniformly adjusting the several screws *b* the frame *a* may be 80 raised or lowered so as to bring the latter into proper position with respect to the printing form 1. Subsequent to this adjustment of the frame *a*, the form 1 is secured in position therein by tightening the clamping screws *d*. A frame *h*, in which the rubber cloth 2 is tightly stretched, is attached by hinges *k* to the frame *a*. The rubber cloth is fixed to the side member *h*¹ of the frame *h* lying next the hinge by a clamping bar *f* and to the front adjustable side member *h*² by means of a similar clamping bar *e*, while it is at first not rigidly fixed to the two side members *h*³ and *h*⁴ of the frame *h*, but attached, so as to be capable of giving. This is effected by the rubber cloth 2 being held in the side members *h*³ and *h*⁴ by clamping devices *g* and slotted clamping bars *m*, which are adapted to slide easily in guiding grooves *c* of the side members *h*³ and *h*⁴ of the frame, 100 until, by adjusting the tensioning member *h*², the rubber cloth has been given the required uniform tension in all directions, in which position the clamping devices *g* are fixed by tightening the screws, which pass through the slots in the clamp bar *m*, the rubber cloth being thus secured in its stretched state. By lateral guide plates *l* on the hinged frame *h*, which are adapted to engage the sides of the frame *a*, the relative adjustment of the two frames is secured, so that there can be no lateral relative movement. 115

For operating the apparatus the frame *h* is hinged over on to the form 1, care being taken that the rubber cloth 2 shall not touch the printing surface of the form 1, but shall maintain a small distance *x* from it (Fig. 4). On the rubber cloth, which forms a perfectly even, tightly stretched surface, being brought in contact with the form 1 by the vertical pressure of the scraper 3, the cloth is pressed down at an inclined angle in such a manner that it can only come in contact with the surface of the form along a straight line, which travels from one side 125 to the other. 130

of the form to the other. The sharp and hard application of pressure by the scraper is eased and caused to be uniform by the oppositely acting tensional force of the rubber cloth, which makes the pressure of the scraper adaptable to the surface in a way which is impossible by any other printing process, the present method thus having all the advantages obtainable with the offset 10 cylinder machine.

In the present method, however, it is unnecessary to make ready specially, as no rigid support is used and an adaptability to the form is obtained, such as is impossible 15 even when using a cylinder in fixed bearings.

What we claim is:—

1. A method of producing prints in an ordinary lithographic hand-press, consisting in tightly stretching the rubber cloth 20 evenly in all directions in the part of the frame adapted to hold it, bringing the stretched cloth over but not into contact with the form, thereupon pressing the cloth into contact with the form by means of the 25 vertical pressure of a scraper along the edge of the scraper and running the carriage with the frame through the press under the scraper, as and for the purpose set forth.

2. A method of producing prints in an ordinary lithographic hand-press, consisting in tightly stretching the rubber cloth evenly 30 in all directions in the part of the frame adapted to hold it, bringing the stretched cloth over but not into contact with the

form, pressing the cloth into contact with the form by means of the vertical pressure of a scraper along the edge of the scraper thereby transferring a colored impression from the form to the rubber cloth, inserting a thin foil between the form and the 40 cloth, and thereupon making an impression on both sides of the foil in one operation of the press.

3. An apparatus for producing prints in an ordinary lithographic hand-press, comprising a four-sided frame capable of holding the printing form and adapted to rest on the carriage of the press, a rubber cloth, an adjustable frame hinged to the said frame and comprising four side members, 45 the member opposite the hinged member being adjustable, means for attaching the rubber cloth to the hinged and adjustable side members of the hinged frame, an adjustable clamping device for attaching the cloth 50 to the two other side members of the adjustable frame, said clamping devices being freely movable with the rubber cloth incident to stretching thereof by the adjustable member of the adjustable frame and also 55 being capable of being fixed in an adjusted position.

In testimony whereof we affix our signatures.
